UNITED STATES PATENT OFFICE.

BANCROFT G. BRAINE, OF NEW YORK, N. Y., ASSIGNOR TO THE RAIL JOINT COMPANY, OF NEW YORK, N. Y., A CORPORATION OF NEW YORK.

RAIL-JOINT.

1,103,394.

Specification of Letters Patent. Patented July 14, 1914.

Application filed March 31, 1913. Serial No. 757,948.

To all whom it may concern:

Be it known that I, BANCROFT G. BRAINE, a citizen of the United States, residing at New York city, in the county of New York and State of New York, have invented certain new and useful Improvements in Rail-Joints, of which the following is a specification.

This invention relates to an improvement 10 in rail joints, and has for its object a novel and practical combination of features which provide a rail joint possessing great strength and stiffness combined with adjustability and resilience.

15 To this end the invention contemplates an improvement wherein a rail joint bar is combined with a separate rail-supporting base plate and a wooden or equivalent filler member, preferably of the reversible type, where- 20 by a joint of maximum strength and efficiency is obtained while at the same time permitting free endwise movement of the rail ends in the joint, thus allowing for contraction and expansion.

25 Also, the improved construction is intended to insure positive and permanent alinement of the joint and the rails and to provide a means for absorbing the noise and vibration of the joint parts, as well as to pro- 30 vide a nut lock for the nuts of the bolts, together with other features of practical advantage that will be readily apparent to those skilled in the art as the details of the invention are fully understood.

35 The essential features of the invention, involving the features of improvement above indicated, are susceptible of structural modification, and adaptation to rail joints of both the standard and insulated types, without 40 departing from the spirit or scope of the invention, but a preferred and practical embodiment of the latter is shown in the accompanying drawings, in which—

Figure 1 is a perspective view of a rail 45 joint, of the standard type, constructed in accordance with the present invention. Fig. 2 is a cross sectional view of the improved rail joint, at the center of the joint.

Like reference characters designate corre- 50 sponding parts in the several figures of the drawings.

In the embodiment of the invention shown in the drawings, the rail joint includes in its general organization the rail ends R, the op- 55 posite side joint bars A and B, the usual

joint bolts and a separate rail-supporting base plate 1 clamped in effective position beneath the rails and extending throughout the entire length of the joint.

Each of the joint bars A and B is of angle 60 bar formation and is provided with a main upright splice member 2 disposed within the fishing spaces of the rails and having at its upper edge a bearing head 3 for engagement beneath the head of the rail, and formed 65 with the lower edge of the splice member 2 is an inclined foot flange 4 overlying and engaging the rail base flange. In addition to the splice member and the foot flange there- 70 of, each side joint bar A and B has formed 75 integrally with the outer edge of the foot flange thereof, a depending portion 5 ar- ranged beyond the edges of the rail flanges and provided with an integral inwardly pro- 80 jecting horizontal base flange or member 6, 85 the base flanges or members 6 of the opposite bars being adapted to lie parallel with the rail bottoms and to provide supporting and clamping shoulders, upon which shoulders rest the opposite edge portions of the sepa- 90 rate rail-supporting base plate 1. In the type of rail joint illustrated, this separate base plate 1 is provided at one side edge with a shoulder 7 which abuts against the edge of the rail flange, and, in conjunction with the 95 inside spikes, serves to hold the joint and rails in alinement. Also, the said base plate may be of a corrugated form, as indicated by the reference character 8 of the drawings, that is to say, it may be provided with one 100 or more grooves or depressions and cor- 105 respondingly elevated bearing surfaces, thus giving it stiffness and strength with a minimum of material, while at the same time the cor- rugated form of base plate is of practical im- 110 portance in providing grooves for receiving sand, cinders, or other gritty foreign sub- stances which might collect between the rail base and the base plate, to cause excessive wear unless removed. However, it will be 100 understood that this is not a necessary fea- 105 ture of the invention as the latter may be carried out with base plates either of a plain or of the corrugated type.

The base plate 1 is of a greater width than the width of the rail bases so as to project a distance beyond the rail flanges at the inner side of the joint, and in connection therewith, the inside joint bar B is sheared off at the ends of its depending portion 5 as indi- 110

cated at 9 in order to permit of the spikes being driven through the spike openings 10 in the exposed inside corners of the base plate, and into contact with the edge of the 5 rail base, thus providing a structure wherein the inside spikes bearing against the edges of the rail base in coöperation with the oppositely located abutment shoulders 7 of the base plate, insure positive and permanent alinement of the joint and of the 10 rails. The central portion of the inside projecting edge of the separate base plate 1 is notched out as at 11 to receive the depending portion 5 of the inside bar B, 15 thereby providing an interlocking between the said bar and the base plate which prevents any relative endwise movement.

The structural characteristics of the outside joint bar A and the elements coöperating therewith are of special importance in 20 the present invention. In this connection it is to be observed that the outside bar A, in addition to the features of construction specified is provided at its upper edge with a laterally projecting reinforcing top flange 12 which extends to a distance beyond the outer sides of the rail heads, and is provided on its under surface with an inclined bearing face 13 corresponding to the inclined 25 bearing face 14 at the upper side of the foot flange 4 of the joint bar, and preferably disposed at the same angle as the latter, thus providing the joint bar A with a longitudinal channel at the outer side thereof which 30 is adapted to accommodate therein a wooden or equivalent compressible filler member or block 15.

The filler member or block 15 is preferably of the reversible type, that is capable 40 of being reversed end for end or top for bottom, and to provide for this the said filler member or block is of a symmetrical formation, the same being formed at top and bottom with double similar inclined bearing 45 surfaces 16 which are adapted to respectively engage the bearing faces 13 and 14 of the joint bar A and the upper and lower inside bearing surfaces 17 and 18 of a channeled bolt strap 19 capping the outside portion 50 of the filler member or block. The said bolt strap 19 is preferably made of channel form with top and bottom flanges respectively overlying and underlying the

filler, thus protecting the latter to a large degree from moisture and other destructive 55 agencies, and adding to the compactness and rigidity of the joint. As indicated, these top and bottom flanges of the bolt strap are preferably disposed at an angle equal to the angle of the under surface of the top 60 flange 12 and the upper surface 14 of the foot flange 4 of the outside joint bar A to admit of the reversible functions of the filler. In addition to its reversibility, it will be noted that the compressible filler 65 forms a nut lock and absorbs noise and vibration of the joint parts, and allows free endwise movement of the rail ends in the joint, thus allowing for contraction and expansion, while the channeled bolt strap also 70 helps to compactly bind together the entire joint structure.

I claim:

1. A rail joint, comprising in combination with the rails, a base plate, opposite 75 joint bars having a clamping engagement with the base plate, and one of which is provided with a channeled outer side, a compressible filler member seated in said channeled outer side of one of the joint bars, and 80 a channeled bolt strap receiving the outer side and top and bottom of the filler.

2. A rail joint, comprising in combination with the rails, a base plate, opposite 85 joint bars having a clamping engagement with the base plate, and one of which bars is provided with a channeled outer side, a reversible compressible filler member registering within the channeled bar, and a channeled bolt strap also receiving the filler 90 and having its flanges disposed at corresponding angles to the angular faces of the filler.

3. A rail joint including in combination 95 with the rails, a joint bar having a channeled outer side, a reversible filler registering with the channel of said bar, and a channeled bolt strap receiving the filler and having its flanges disposed at a corresponding angle to the angular faces of the filler.

In testimony whereof I hereunto affix my signature in the presence of two witnesses.

BANCROFT G. BRAINE.
